UNITED STATES PATENT OFFICE.

GEORGE W. EMRICK, OF BROOKLYN, NEW YORK, ASSIGNOR TO EASTERN TUBE AND TOOL COMPANY, A CORPORATION OF NEW YORK.

TAPPING ATTACHMENT.

Application filed June 23, 1922. Serial No. 570,466.

To all whom it may concern:

Be it known that I, GEORGE W. EMRICK, a citizen of the United States, and residing at Brooklyn, in the county of Kings and 5 State of New York, have invented certain new and useful Improvements in Tapping Attachments, of which the following is a specification, such as will enable those skilled in the art to which it appertains to make and 10 use the same.

This invention relates to tapping attachments for use in connection with drill presses and similar machines, and the object of the invention is to provide means whereby 15 a tap mounted in connection with the attachment may be automatically rotated in one direction in the operation of cutting the threads; a further object being to provide means for permitting of the slipping of the 20 driving means for said tap in the event of the tap striking an obstruction or the like to prevent the breaking of the tap; a further object being to provide means for automatically reversing the direction of rotating the 25 tap in the operation of withdrawing the tap from a predetermined workpiece, both of said driving means involving a floating double face cone clutch device adapted to be moved into and out of engagement with op- 30 ositely and positively rotated conical drive members and also capable of slippage over said members when the tool is subjected to excess stress or strain, and with these and other objects in view the invention consists 35 in a device of the class and for the purpose specified which is simple and compact in construction, efficient in use and which is constructed and operated as hereinafter described and claimed.

40 The invention is fully disclosed in the following specification, of which the accompanying drawing forms a part, in which the separate parts of my improvement are designated by suitable reference characters in 45 each of the views, and in which:—

Fig. 1 is a partial transverse sectional view through my improved tapping attachment and showing the parts in one position of operation;

50 Fig. 2 a view similar to Fig. 1 but showing parts in another position;

Fig. 3 a sectional plan view on the line 3—3 of Fig. 1;

55 Fig. 4 a partial section on the line 4—4 of Fig. 1; and,

Fig. 5 a section on the line 5—5 of Fig. 4 and on an enlarged scale.

In practice, a substantially cup-shaped casing 5 is employed, said casing being provided with an extension 6 at one side thereof, 60 and the casing 5 and extension 6 are open at the top and adapted to be closed by a cover 7 held in position by screws 8, and at one side of the extension 6 is a projecting boss 9 in connection with which a rod 10 may 65 be connected to facilitate the mounting and handling of the attachment.

Approximately centrally of the bottom of the casing 5 is a bearing portion 11 in which is mounted a brass or bronze bushing 12, and the cover 7 is provided with a similar bearing 13 provided with a bushing 14 and a tapered shaft 15 by means of which the attachment may be mounted in connection with a suitable machine is provided with a threaded portion 16 adapted to be threaded into a sleeve extension 17 of the shaft 18 which extends into the casing 5, said sleeve extension 17 operating in the bushing 14. The shaft 15 is provided with 70 a flange 15^a and the shaft 18 with a flange 18^a which retain both of the shafts 15 and 18 against vertical movement in the casing. 75

The supplemental shaft 18 extends downwardly into a sleeve 19 which forms a guide 80 for the lower end of the supplemental shaft 18, and the sleeve 19 is mounted in the bushing 12 and the upper or inner end thereof is guided by the supplemental shaft 18. The upper or inner end of the sleeve 19 is 85 threaded as shown at 20 to receive a ring-shaped lock nut 21, which is permanently set when placed in position and serves to hold a conical friction clutch 22 in position on the sleeve 19, said sleeve being provided with a 90 flange 23 upon which the cone rests, and the nut 21 limits the upward movement of the clutch 22 on said sleeve. The top plate 24 of the clutch 22 is provided around the sleeve 19 with notches 25 and the flange 23 is provided with similar notches 26 arranged at 95 right angles to the notches 25, and a floating ring-shaped member 27 is mounted between the top plate 24 of the clutch 22 and the flange 23, and the member 27 is provided 100 on opposite sides with projecting members 28 and 29 which are adapted to operate in connection with the notches 25 and 26 respectively to interlock the sleeve 19 with the clutch 22 and yet permit of the radial move- 105

110.

ment of the clutch 22 on the sleeve in practically any direction thus facilitating the centering of the clutch as hereinafter set out.

The clutch 22 is provided with inner and outer fibrous facings 30 and 31, and the inner facing 30 is adapted to operate in connection with a conical member 32 rotatably mounted upon the sleeve 19 and provided with a gear face 33, and the outer facing 31 is adapted to operate in connection with another conical member 34 which is fixed to the flange 18^a of the shaft 18 by screws 35 to form an integral part thereof, and the member 34 is provided with a large gear 36 which is in the form of a ring secured to the member 34.

In the extension 6 of the casing 5 and centrally thereof is mounted a vertical pin or bearing 37 upon which is mounted within the casing 5, or the extension 6 thereof, a sleeve 38 the upper end of which is provided with a gear 39 which meshes with the gear 36 and the lower end of said sleeve is provided with a gear 40, which meshes with a pinion 41 mounted centrally between the pin 37 and the sleeve 19 on a suitable pin or other bearing, and the pinion 41 is adapted to mesh with the gear 33 on the member 32.

The sleeve 19 is provided at its lower end with a tapered pin extension 42 in connection with which a suitable chuck 43 is adapted to be mounted, whereby a tap or similar tool 44 may be connected with the sleeve 19 and the friction cone clutch 22 coupled therewith.

From the foregoing description it will be apparent that the tapered shaft 15 is connected with a suitable machine in the usual manner and is rotated by the operative mechanisms of the machine, and the rotation of this shaft will correspondingly rotate the member 34 and the gear 36 mounted thereon, which operation will rotate the sleeve 38 and the gears 39 and 40 thereof, and the conical member 32 will also be rotated through the gears 41 and 33 which are in operative connection with the gear 40, and this gearing will rotate the member 34 in one direction and the member 32 in the opposite direction and the conical clutch member 22 is adapted to be moved into and out of engagement with the separate members 32 and 34 to control the direction of rotation of the tool 44 mounted in the chuck 43.

Normally the clutch member 22 is in engagement with the conical member 32 and in the operation of tapping a hole in a suitable workpiece, when the tool or tap 44 comes in contact with the workpiece, the pressure thereon will force the conical clutch member 22 upwardly to bring the friction facing 31 thereof into engagement with the inner conical face of the member 34 to cause the tool 44 to be rotated in the proper direction to cut the threads in the hole in the workpiece,

and in this operation and in the event of the tool striking an obstruction, or in the event of the presence of undue stress or strain on the tool, and by reason of the taper employed on the clutch member 22 and member 34 a 70 slippage is allowed between said members thus preventing or avoiding the breaking of the tool 44. After the hole in the workpiece has been threaded and in withdrawing or removing the tool from the workpiece, the 75 conical clutch member 22 or the friction facing 30 thereof, is moved into engagement with the member 32 and the tool is rotated in the opposite direction in this operation, and the same slippage is provided in the operation of removing the tool, or in the reverse rotation thereof. It will also be apparent that by reason of the method of coupling the conical clutch member with the sleeve 19 through the floating ring 27 regardless of 80 any unevenness, bulges, depressions or the like in either of the friction facings 30-31, said friction facings will find a seat in or on the members 34 and 32, it being understood that the conical clutch member is capable of radial movement in every direction by reason of what might be called a universal Oldham coupling between said clutch member and the sleeve 19 in connection with 85 which the tool is mounted.

It will also be apparent that I provide suitable means for oiling the various working parts of my improved device, and by reason of the mounting of the clutch member 22, within and between the separate members 32 and 34, no oil used for lubricating purposes can come in contact with the friction facings 30-31 of the clutch member thus keeping such friction facings in proper condition at all times, and while I have shown certain details of construction for carrying my invention into effect, it will be understood that various changes therein and modifications thereof may be made, within the scope of the appended claims, without departing 100 from the spirit of my invention or sacrificing its advantages.

Having fully described my invention, what I claim as new and desire to secure by Letters Patent, is:—

1. A device of the class described comprising two rotatable conical members, one of said members being located within the other, means for rotating said members in opposite directions, a floating clutch mounted between the conical faces of said members and capable of movement toward and from the conical face of either member, and a universal mounting for said clutch to facilitate the centering thereof in connection with the separate members.

2. A device of the class described comprising two rotatable conical members, one of said members being located within the other, means for rotating said members in

opposite directions, a floating clutch mounted between the conical faces of said members and capable of movement toward and from the conical face of either member, and a universal mounting for said clutch to facilitate the centering thereof in connection with the separate members, said clutch being provided on its inner and outer faces with clutch facings adapted to operate in connection with the separate conical members.

3. A device of the class described comprising two rotatable conical members, one of said members being located within the other, means for rotating said members in opposite directions, a floating clutch mounted between the conical faces of said members and capable of movement toward and from the conical face of either member, a universal mounting for said clutch to facilitate the centering thereof in connection with the separate members, said clutch being provided on its inner and outer faces with clutch facings adapted to operate in connection with the separate conical members, and the taper of said conical members and said clutch being such as to permit slippage of the clutch on said members.

30 4. A device of the class described comprising two rotatable conical members, one of said members being located within the other, means for rotating said members in opposite directions, a floating clutch mounted between the conical faces of said members and capable of movement toward and from the conical face of either member, a universal mounting for said clutch to facilitate the centering thereof in connection with the separate members, said clutch being provided on its inner and outer faces with clutch facings adapted to operate in connection with the separate conical members, the taper of said conical members and said clutch being such as to permit slippage of the clutch on said members, and means for coupling a tool in connection with said clutch.

50 5. A tapping attachment of the class described comprising a suitable casing, a conical member rotatably mounted in said casing and provided with an extension adapted to be connected with a suitable power unit whereby said member may be rotated, another conical member mounted in said casing and within said first named member and geared in connection with said first named member in such manner as to rotate in a direction opposite to that of said first named member, a clutch mounted between said members and provided with friction facings adapted to operate in connection with the conical faces of either of said members, and said clutch being provided with a movable mounting to permit of its

centering upon the facings of the separate members.

6. A tapping attachment of the class described comprising a suitable casing, a conical member rotatably mounted in said casing and provided with an extension adapted to be connected with a suitable power unit whereby said member may be rotated, another conical member mounted in said casing and within said first named member and 70 geared in connection with said first named member in such manner as to rotate in a direction opposite to that of said first named member, a clutch mounted between said members and provided with friction facings 75 adapted to operate in connection with the conical faces of either of said members, a shaft member extending through the casing and in connection with which said clutch is mounted, and means to provide radial 80 movement on said shaft member.

7. A tapping attachment of the class described comprising a suitable casing, a conical member rotatably mounted in said casing and provided with an extension adapted 90 to be connected with a suitable power unit whereby said member may be rotated, another conical member mounted in said casing and within said first named member and 95 geared in connection with said first named member in such manner as to rotate in a direction opposite to that of said first named member, a clutch mounted between said members and provided with friction facings 100 adapted to operate in connection with the conical faces of either of said members, a shaft member extending through the casing and in connection with which said clutch is mounted, means to provide radial movement 105 of the clutch on said shaft member, and means whereby a suitable tool may be mounted in connection with said shaft member.

8. A tapping attachment of the class described comprising a substantially cup-shaped casing provided at one end with an extension, said casing being open at the top and provided with a detachable cover, a conical member mounted in connection with the cover of the casing and rotatable therein 110 and provided with an extension by means of which said member may be rotated, another conical member mounted in the casing and within said first named member a gear unit 115 mounted within the extension of the casing and provided with gear members in operative connection with the separate conical members whereby said conical members may be rotated in opposite direction, and a clutch member mounted in said casing between the 120 conical faces of said members.

9. A tapping attachment of the class described comprising a substantially cup-shaped casing provided at one end with an extension, said casing being open at the top 130

- and provided with a detachable cover, a conical member mounted in connection with the cover of the casing and rotatable therein and provided with an extension by means 5 of which said member may be rotated, another conical member mounted in the casing and within said first named member, a gear unit mounted within the extension of the casing and provided with gear members in 10 operative connection with the separate conical members whereby said conical members may be rotated in opposite direction, a clutch member mounted in said casing between the conical faces of said members, a shaft extending through the bottom of the casing, and means for movably mounting said clutch in connection with said shaft to 15 permit of the radial movement of said clutch thereon.
10. A tapping attachment of the class described comprising a substantially cup-shaped casing provided at one end with an extension, said casing being open at the top and provided with a detachable cover, a conical 20 member mounted in connection with the cover of the casing and rotatable therein and provided an extension by means of which said member may be rotated, another conical member mounted in the casing and within said first named member, a gear unit 25 mounted within the extension of the casing and provided with gear members in operative connection with the separate conical members whereby said conical members may be rotated in opposite direction, a clutch member mounted in said casing between the 30 conical faces of said members, a shaft extending through the bottom of the casing, means for movably mounting said clutch in 35 connection with said shaft to permit of the radial movement of said clutch thereon, and said clutch and shaft being capable of vertical movement in the casing to permit of the movement of said clutch into and out of 40 engagement with the separate members.
11. A tapping attachment of the class described comprising a substantially cup-shaped casing provided at one end with an extension, said casing being open at the top 45 and provided with a detachable cover, a conical member mounted in connection with the cover of the casing and rotatable therein and provided with an extension by means of which said member may be rotated, another conical member mounted in the cas- 50
- ing and within said first named member, a gear unit mounted within the extension of the casing and provided with gear members in operative connection with the separate conical members whereby said conical members may be rotated in opposite direction, a clutch member mounted in said casing between the conical faces of said members, a shaft extending through the bottom of the casing, means for movably mounting said clutch in 55 connection with said shaft to permit of the radial movement of said clutch thereon, said clutch and shaft being capable of vertical movement in the casing to permit of the movement of said clutch into and out of engagement with the separate members, means for mounting a tool in connection 60 with said shaft, and said clutch member being provided with inner and outer clutch facings adapted to operate in connection with the tapered faces of said conical members. 65
- In testimony that I claim the foregoing as my invention I have signed my name this 21st day of June, 1922.

GEORGE W. EMRICK.
